UNITED STATES PATENT OFFICE

124,056

DESIGN FOR A SHOE DRESSING APPLICATOR

Alfred R. Babcock, Chicago, Ill.

Application August 28, 1940, Serial No. 94,692

Term of patent 14 years

To all whom it may concern:

Be it known that I, Alfred R. Babcock, a citizen of the United States, residing at Chicago, in the county of Cook and State of Illinois, have invented a new, original, and ornamental Design for a Shoe Dressing Applicator, of which the following is a specification, reference being had to the accompanying drawing, forming a part thereof, in which:

Figure 1 is a top plan view of a shoe dressing applicator showing my new design; Figure 2 is a side elevational view thereof; Figure 3 is a bottom plan view thereof; and Figure 4 is an enlarged front elevational view of the same.

I claim:

The ornamental design for a shoe dressing applicator, as shown.

ALFRED R. BABCOCK.
